SLEEPING CAR CONSTRUCTION

Earl J. W. Ragsdale, Norristown, Pa., assignor to
 Edward G. Budd Manufacturing Company,
 Philadelphia, Pa., a corporation of Pennsylvania

Application April 7, 1937, Serial No. 135,452

5 Claims. (Cl. 105—316)

This invention relates to the construction and arrangement of seats and beds in the sleeping compartments of vehicles, particularly railroad cars.

Where sleeping compartments are equipped, as is usual, with seats which are convertible into berths or beds for night service, such seats, when adjusted for day service, afford no facilities for resting in a reclining position. If, for any reason, the occupant wishes to lie down during the day, it is necessary to have the porter shift the seats to form a bed, as for regular night service, and this involves considerable labor and inconvenience.

The object of the present invention is to provide a sleeping compartment with seats so constructed and arranged that while they may be converted into a bed, for night service, in the usual way, one of such seats may, when adjusted for day service, be conveniently employed, without further change, as a full length couch or day bed.

To this end, the invention comprises the combination and arrangement of parts hereinafter described and claimed, and shown in the accompanying drawing, forming part of this specification, and in which:

Fig. 1 is a fragmentary plan view of a railroad car having a sleeping compartment equipped in accordance with the invention, and showing the equipment as it appears when arranged for day service; and

Fig. 2 is a similar view showing the equipment arranged for night service.

Referring to the drawing in detail, I designates the side walls of the car, and 2 a longitudinal partition forming the outer wall of the sleeping compartment A and forming between itself and the car wall 1 a passageway B. The wall 2 is preferably provided with a door 3 affording access from the passageway to the sleeping compartment. Transverse walls 4, extending between the wall 2 and the wall of the car, divide the compartment A from adjoining compartments or rooms on either side.

My improved equipment comprises a double width seat, having the bottom section 5 and the back section 6. Opposite this double width seat is a triple width seat comprising a bottom section 7 and back section 8 of double width and of the convertible type, and an additional section 9 of single width.

The double width seats 5, 6, and 7, 8 are arranged facing each other in the usual manner, and the sections are movable or adjustable so

that they may be converted into a bed. When so converted, the bottom sections 5 and 7 are shifted toward each other into substantial contact, as shown in Fig. 2, while the back sections 6 and 8 are shifted to horizontal position, so that the four sections 5, 6, 7 and 8 cooperate to form a bed, in the well known manner. Meanwhile, the single width seat 9, which is structurally independent of the double width seat sections 7 and 8, remains in its original position and may be employed as a chair.

Referring again to Fig. 1, in which the parts are shown as adjusted for day service, it will be seen that in my improved arrangement the single width seat 9 is disposed in line with the double width seat 7 and with it forms a triple width seat which is long enough to constitute and is capable of use as a full length couch or day bed.

Thus it will be seen that the double width seat section 7, when in one position, cooperates with the opposite double width seat 5 to form a bed for night service, and, when in another position, cooperates with the single width seat 9 to form a couch for day service.

From the foregoing, it will therefore be seen that my improved equipment provides a couch on which the occupant of the compartment or cabin may recline, when the seats are adjusted for day service, while at the same time the equipment provides the usual facilities by which a bed of standard size is available for night service.

What I claim is:

1. A sleeping compartment having a pair of seats of double width facing each other, the bottom and back sections of each seat being movable into positions where they all cooperate to form a bed, and a third seat of single width mounted in line with one of said seats of double width and forming therewith a full length couch.

2. A sleeping compartment having opposed seats, one of double width and the other of triple width adequate to provide a full length couch, the latter comprising a single width portion and an independently movable double width portion, the bottom and back sections of said double width portion being adjustable, and adapted to cooperate with similar sections of the first mentioned double width seat to form a bed.

3. A sleeping compartment for a side aisle car and extending from the aisle to the side of the car opposite said aisle and having a pair of opposed, convertible, double width seats, and a third seat in line with one of said double width

seats, and forming therewith a triple width seat, capable of use as a full length couch.

4. The combination with a first double width convertible seat, and a single width seat, of a second double width convertible seat, and means whereby said second double width seat may be arranged to cooperate either with said first double width seat to form a bed, or with said single seat to form a full length couch.

5. A sleeping compartment including a multiple part seat of a length adequate for use as a full length couch, and a seat opposite to a part of the first seat, the opposite seat and the part of the first seat being movable jointly to a bed forming position, the remainder of the first seat remaining a seat alongside the bed. 5

EARL J. W. RAGSDALE.
